(57) **CLAIM**

I claim the ornamental design for a bib, as shown and described.

DESCRIPTION

FIG. 1 is a rear perspective view of bib, showing a first embodiment of my new design;

FIG. 2 is a front elevational view of FIG. 1;

FIG. 3 is a rear elevational view of FIG. 1;

FIG. 4 is a right-side elevational view of FIG. 1;

FIG. 5 is a left-side elevational view of FIG. 1;

FIG. 6 is a top plan view of FIG. 1;

FIG. 7 is a rear perspective view of a second embodiment thereof;

FIG. 8 is a front elevational view of FIG. 7;

FIG. 9 is a rear elevational view of FIG. 7;

FIG. 10 is a right-side elevational view of FIG. 7, the left-side elevational view being a mirror image thereof;

FIG. 11 is a perspective view of a third embodiment thereof;

FIG. 12 is a front elevational view of FIG. 11;

FIG. 13 is a rear elevational view of FIG. 11;

FIG. 14 is a left-side elevational view of FIG. 11; and,

FIG. 15 is a right-side elevational view of FIG. 11.

The broken lines on the drawing figures represent perforations, and are part of the claimed design. The broken lines at the bottom edge representing an indeterminate height of the design are environmental matter and form no part of the claimed design. It is understood that the top plan views of all embodiments are identical.
